UNITED STATES PATENT OFFICE

EUGENE L. SCHELLENS, OF RIDGEWOOD, NEW JERSEY, ASSIGNOR TO C-S ENGINEERING COMPANY, OF ENGLEWOOD, NEW JERSEY, A CORPORATION OF DELAWARE

LOCOMOTIVE AND SUPERHEATER THEREFOR

Application filed April 2, 1930. Serial No. 440,950.

This invention relates to locomotives and to superheaters for imparting additional heat to the saturated steam prior to its introduction into the engine cylinders.

Superheaters usually have been installed in the smoke box of the locomotive boiler, with the superheater tubes located within certain, and enlarged, fire tubes of the boiler. There are certain disadvantages to this construction and location of the superheater. It is tedious to repair the superheater since usually it is necessary to remove the draft appliances that are located in the smoke box in front of the superheater in order to gain access to the superheater; and the average installation necessitates the removal of the entire smoke box front. The efficiency of the superheater is not as great as it might be because the portions of the superheater tubes that are located in the smoke box or in the portions of the fire tubes immediately in the rear of the smoke box are usually in combustion gases which are at a lower temperature than the superheated steam in the superheater tubes. Consequently, these front portions of the superheater tubes are of little value and may even act to cool the steam. The location of the superheater tubes within the fire tubes necessitates enlarged fire tubes and thus reduces the effective evaporating surface of the boiler and hence reduces the evaporating efficiency over that which the boiler would have if a larger number of smaller fire tubes were used. Furthermore, the superheater is located in the path of partially cooled combustion gases so that the temperature of superheat of the steam is limited.

Thus an object of the present invention is the provision of a locomotive boiler and a superheater therefor which shall be free from the above enumerated objections.

A further object of the invention is the provision of a locomotive boiler having a superheater which is disposed between the fire box and the evaporating tubes of the boiler and thus is in the path of the uncooled combustion gases. It has been found that such an arrangement is highly advantageous as the superheater can be relatively small as compared with the usual superheater and can

have a smaller heating surface, thus taking up less room than the usual superheater and yet furnish a degree of superheat which is higher than can be supplied with the usual superheater.

Another object of the invention is the provision of a superheater that is located as above described and is entirely free and outside of the fire tubes of the boiler so that a large number of small fire tubes can be utilized and thus a large evaporating surface provided even though the length of the fire tubes may be shorter than has been the usual practice.

A further object of the invention is the provision of a locomotive boiler having a superheater located between the fire box and the fire tubes of the boiler and wherein the length of the combustion space between the fire and the entrance to the fire tubes is increased over the usual practice so as to obtain an increased length of passage of the gases before they enter the fire tubes, thereby insuring a more thorough mixture of the combustion gases and better combustion and thereby an increased efficiency.

A further object of the invention is the provision of a locomotive boiler and a superheater therefore arranged as above described and wherein means are interposed between the fire box and the superheater to shield the superheater from the direct radiant heat of the fire, which means can comprise shielding surfaces, as water evaporating conduits.

A further object of the invention is the provision of a locomotive boiler which has siphons between the fire box and the fire tubes, and a superheater which is located between the siphons and the fire tubes.

The superheater embodying the present invention has saturated and superheated steam headers between which the superheating tubes are extended. Due to the location of the superheater between the fire and the fire tubes, the superheater is subjected to high temperatures. For this reason another object of the invention is to provide the superheater and its header with means permitting the free longitudinal expansion and contraction of a superheater header while restraining it from lateral displacement or vibration;

and with means to shield a header from direct contact with the heated combustion gases.

A further object of the invention is generally to improve the construction and operation of boilers and superheaters.

Fig. 1 is a side elevation, partly in section illustrating such elements of a locomotive as are considered necessary to illustrate the present invention.

10 Fig. 2 is a section taken along line 2—2 of Fig. 1 and illustrating in particular an end view of the superheater of Fig. 1, only a sufficient number of superheater tubes necessary to illustrate the construction being shown.

15 Fig. 3 is a section taken along line 3—3 of Fig. 1.

Fig. 4 is an enlarged elevation of the superheater of Fig. 1.

Fig. 6 is a side elevation of a modified form of a superheater.

Fig. 7 is a plan detail taken along line 7—7 of Fig. 6.

25 Fig. 8 is a sectional detail taken along line 8—8 of Fig. 6.

Fig. 9 is a sectional elevation of a further modified form of superheater.

30 Fig. 10 is a transverse elevation taken along line 10—10 of Fig. 9.

Fig. 11 is a detailed sectional elevation illustrating another modified form of superheater.

35 As shown in Fig. 1, the locomotive and the superheater embodying the present invention include the boiler 16 having the grate 18 which supports the fire, the rear tube sheet 20, the front tube sheet 22, the fire tubes 24 which extend between the tube sheets, the 40 smoke box 26, the smoke stack 28, the steam dome 30, and the engine cylinders 32. A plurality of transversely spaced siphons 34 are located in the combustion chamber between the fire and the rear tube sheet 20 in 45 a more or less usual manner to increase the evaporation efficiency of the boiler. Rows of baffle plates 36 are located between the siphons and constitute an arch and extend upwardly from the bottom thereof and are terminated short of the upper ends thereof to 50 provide passages 38 through which the hot combustion gases pass from the fire box 40 beneath said baffle plates to the main portion of the combustion chamber 42 between 55 the siphons and the rear tube sheet.

In accordance with the present invention, the superheater herein generally indicated by the numeral 44 in Fig. 1 is located in said combustion chamber forward of the siphons 34 and in the rear of the rear tube sheet 20. It receives saturated steam from the dry pipe 46, the open end of which is located under the steam dome 30, and superheats the steam and passes the superheated steam through 60 the engine throttle valve 48 and thence

through the pipes 50, but one being illustrated, to the engine cylinders 32. The superheater illustrated in Fig. 1 is shown in greater detail in Fig. 4. The superheater includes the saturated steam header 52 and the superheated steam header 54. The saturated steam header herein consists of a vertically disposed conduit which is closed at the bottom and is open at the top and is secured to and depends from the top of the crown sheet 56 of the boiler and is in communication with the dry pipe 46, the lower end of which is also secured to the crown sheet 56. While the upper end of the header is fixed against movement, means are provided which supports the lower end of the header against lateral movement while permitting it to expand and contract freely in response to temperature variations. For this purpose, the lower end of the header is provided with a depending bracket 58 which has a projection 60 that is vertically loose in a guide plate 62 that is secured to the lower portion of the crown sheet which at this location forms the bottom wall of the combustion chamber. The projection 60 thus is free for vertical movement in said plate, whereby to permit expansion and contraction of the header, but is held against lateral movement.

The superheated steam header 54 is carried by the lower portion of the crown sheet and extends vertically upward in the rear of the saturated steam header. The superheated steam header is closed at the top and is open at the bottom and passes through the bottom portion of the crown sheet and also through the outer shell 64 of the boiler where it connects with a take-off casting 66 that is connected through an expansion joint 68 with the throttle valve 48. The take-off casting may be provided with a series of internally screw-threaded holes 70 for taking off steam for the operation of the various locomotive accessories. The superheated steam header is provided with a jacket 72 which substantially envelops the rear portion of the header and thus shields it from contact with the highly heated combustion gases that would otherwise impinge against it. The jacket 72 is integral with the header and has an opening 74 in the lower end which communicates through the bottom portion of the crown sheet, or the bottom wall of the combustion chamber, with the water space thereunder. The jacket is also open at the top and is fixed to and communicates with the steam space above the crown sheet, thereby providing a circulating path 75 for water and steam and forming in effect a siphon which increases the evaporative effect of the boiler and at the same time protects the superheated steam header from the action of the highly heated combustion gases.

The superheated steam header is provided with vertically spaced forwardly extended hollow ears 76 to the opposite sides of which

transversely extended parallel and horizontal auxiliary or branch headers 78 are fixed as by welding. The outer ends of said auxiliary headers are closed while the inner ends are in communication with the interior of the main header through the ears 76. The saturated steam header is provided with similar ears 80 which are rearwardly extended toward the superheated steam header; and auxiliary headers 82 similar to said headers 78 are fixed to said ears. The auxiliary headers 82 are higher in elevation than the respective headers 78. Sets or bundles 83 of superheater tubes 84 are connected between the auxiliary headers of the two main headers, each bundle consisting of a plurality of superposed vertically spaced horizontal passes of tube, the top pass being fixed, as welded, to and in communication with a saturated steam auxiliary header and the lower pass being similarly connected to and in communication with the corresponding auxiliary superheated steam header. A considerable number of such bundles are connected to and extended between the auxiliary headers on both sides of the main headers. Thus the saturated steam entering the saturated steam header 52 is caused to traverse the bundles of superheater tubes and become superheated. The superheated steam passes from the tubes into the main superheated steam header and thence to the engine cylinders.

With the above described arrangement, the superheater tubes 84 can be relatively short in length since they are located in the highly heated gases in the combustion chamber 42 and can thus supply superheated steam at a high temperature to the engine cylinders. A relatively large number of superheater tubes can be utilized since they can be closely spaced as their location is not determined by the presence of the fire tubes of the boiler and the dimensions of the fire tubes. The fire tubes 24 can be made smaller in diameter than can be the case where the superheater pipes are located within the fire tubes and thus an increased evaporating surface of fire tubes can be provided.

The superheater is shielded from the radiant heat of the fire by the baffle or arch 36 and also by the siphons 34. The particular construction of siphon herein shown while now common in the art can be replaced by any other suitable form of water and steam containing passage, not necessary to illustrate, that functions to shield the superheater from excessive radiant heat.

The superheater is so constructed and located that it is conveniently accessible when the boiler is cold; and the superheater is spaced from the rear tube sheet 20 so that the rear tube sheet is also accessible.

The superheated steam outlet of the superheater is through the bottom of the boiler shell; and the throttle valve 48 and the pipes

50 which conduct superheated steam to the engine cylinders are also below the boiler shell. Thus the top of the locomotive is clear of all large size piping and fittings which would obstruct the vision of the engine driver 70 and impose special clearance limitations and present an unsightly appearance.

While the superheater illustrated in Figs. 1 through 5 is for many purposes the preferred construction, yet it may be advantageously modified for certain purposes. In Fig. 6, the superheater tubes 84a are of spiral formation and the ends thereof are connected to branches 86 of the auxiliary headers 78a, 82a. In the modification illustrated in Figs. 9 and 10, the saturated steam header 88 is located in the steam space between the crown sheet 56 and the outer boiler shell 64 and extends longitudinally of the boiler and has its upper end 90 in the steam dome 30. The header is provided with oppositely extended auxiliary headers 92 which extend through the crown sheet and are welded therein. The superheated steam header 94 extends through the outer shell and the crown sheet of the boiler at the bottom thereof and has two rearwardly extended auxiliary headers 96 which are disposed beneath the auxiliary headers 92. Vertically extended spirally wound superheater coils 98 are connected between the auxiliary superheated and saturated steam headers. In the modification shown in Fig. 11 the crown sheet 56a which comprises the side wall of the combustion chamber is made as a steel casting and has the saturated steam header 100 and the superheated steam header 102 integral therewith. Hollow ears 104 extend from the saturated steam header into the interior of the combustion chamber and other hollow ears extend upwardly from the superheated steam header into the combustion chamber, these ears being integral with the wall of the combustion chamber and also with the header. 105 Pipes 108 constituting branch headers, which extend in opposite directions from the ears, are welded thereto and receive the plurality of inclined superheater tubes 110 which are arranged in parallel form, as shown in Fig. 1. 110

I claim:

1. A locomotive boiler having a combustion chamber, a rear tube sheet forming the front wall of said chamber, fire tubes terminated at said tube sheet, and a superheater 120 for the steam delivered from said boiler located in said combustion chamber in the rear of said tube sheet and free and independent of said fire tubes having independent saturated and superheated steam headers one of which is carried by the top wall and the other by the bottom wall of said combustion chamber.

2. A locomotive boiler having a combustion chamber, evaporating tubes communicating 125

with said combustion chamber, and a superheater for superheating the steam supplied by said boiler having saturated and superheated steam headers which are located at least in part in and are extended respectively through the top and bottom parts of said combustion chamber, and superheater tubes connected between said headers.

3. A locomotive boiler having a combustion chamber located within and surrounded by the water space of the boiler, a rear tube sheet which forms the front wall of said combustion chamber, evaporating tubes terminated at said tube sheet, and a superheater for superheating the steam supplied by said boiler having superheated and saturated steam headers which are located at least in part in said combustion chamber in the rear of said tube sheet and are extended respectively through the top and bottom parts of said combustion chamber and the water space, and superheater tubes connected between said headers.

4. A locomotive boiler having a combustion chamber, a rear tube sheet which forms the front wall of said chamber, evaporating tubes terminated at said tube sheet, and a superheater for superheating the steam supplied by said boiler having a saturated steam header which is located at least in part in said combustion chamber and is carried by the top wall thereof in the rear of said tube sheet, a superheated steam header which also is located at least in part in said combustion chamber and is carried by the bottom wall of said chamber in the rear of said tube sheet, and superheater pipes located in said combustion chamber and extended between said headers.

5. A locomotive boiler having evaporating tubes, a combustion chamber communicating with said tubes, and a superheater located in said combustion chamber for superheating the steam supplied by said boiler, said superheater having a header which is located in said combustion chamber and is fixed to a wall thereof and extends toward the opposite wall thereof, said opposite wall and said header having loosely interengaged parts that hold said header against lateral movement while permitting said header to expand and contract longitudinally.

6. A locomotive boiler having evaporating tubes, a combustion chamber communicating with said tubes, and a superheater located in said combustion chamber for superheating the steam supplied by said boiler, said superheater having a header which is located in said combustion chamber and is fixed to a wall thereof and extends toward the opposite wall thereof, and means for holding the free end of said header against lateral movement while permitting the header to expand and contract longitudinally.

7. A locomotive boiler having a combustion

chamber, evaporating tubes in communication with the combustion gases that pass through said chamber, and a superheater for superheating the steam supplied for said boiler having superheater tubes located in said combustion chamber in the rear of said evaporating tubes, a saturated steam header connected with said tubes and carried by and having a connection which is extended through the top wall of said chamber and communicates with the steam space in said boiler, and a superheated steam header which also is connected with said superheated steam tubes and which is carried by and has a superheated steam outlet through the bottom wall of said chamber.

8. A locomotive boiler having a combustion chamber, a rear tube sheet which forms the front wall of said chamber, fire tubes terminated at said tube sheet, and a superheater located in said combustion chamber in the rear of said tube sheet for superheating the steam supplied by said boiler having a saturated steam header which is carried by the top wall of said combustion chamber and extends downwardly therein at the rear of said tube sheet, a superheated steam header which is carried by the bottom wall of said combustion chamber and extends upwardly therein at the rear of said saturated steam header, horizontal auxiliary headers which are carried by said superheated and saturated steam headers and extend horizontally in opposite directions therebeyond, and superheater tubes extended between said auxiliary saturated and superheated steam headers.

9. A locomotive boiler having a combustion chamber, siphons in said combustion chamber, evaporating tubes communicating with said chamber in front of said siphons, and a superheater located in said combustion chamber between said siphons and said evaporating tubes for superheating the steam supplied from said boiler and having a saturated steam header carried by the top of said combustion chamber and a superheated steam header carried by and having an outlet through the bottom of said combustion chamber forwardly of said siphons.

10. A locomotive boiler having a crown sheet which forms a combustion chamber, a rear tube sheet which forms the front wall of said combustion chamber, fire tubes terminated at said tube sheet, siphons extended between the top and bottom of said crown sheet in said combustion chamber in the rear of said tube sheet and communicating with the steam space in said boiler above said crown sheet and with the water space in said boiler below the bottom portion of said crown sheet, a grate which supports the fire located beneath said siphons, and a superheater located in said combustion chamber between said siphons and said rear tube sheet for superheating the steam supplied by said

boiler and having a saturated steam header carried by and having an inlet through the top of said crown sheet with said steam space, and also having a superheated steam header 5 carried by and having an outlet through the water space under said crown sheet.

11. A locomotive boiler having a crown sheet which forms a combustion chamber, a rear tube sheet which forms the front 10 wall of said combustion chamber, fire tubes terminated at said tube sheet, siphons extended between the top and bottom of said crown sheet in said combustion chamber in the rear of said tube sheet and communicating 15 with the steam space in said boiler above said crown sheet and with the water space in said boiler below the bottom portion of said crown sheet, a grate which supports the fire located beneath said siphons, and a 20 superheater located in said combustion chamber between said siphons and said rear tube sheet for superheating the steam supplied by said boiler and having a saturated steam header carried by and having an inlet 25 through the top of said crown sheet with said steam space, and also having a superheated steam header carried by and having an outlet through the water space under said crown sheet, said siphons being spaced apart 30 transversely of said expansion chamber, and a fire arch located between said siphons, said siphons and fire arch constituting means which shields said superheater from the radiant heat of the fire.

35 12. A boiler having evaporating tubes, means including a combustion chamber to supply a heated gas to said tubes, a superheater located in the gas stream in said combustion chamber for superheating the steam 40 supplied by said boiler and having saturated and superheated steam header structures, one of said structures being extended across said combustion chamber and connected to the top and bottom thereof and having a water jacket 45 enclosing at last a part of the steam space thereof, said jacket having a water inlet which is in communication through the bottom of said combustion chamber with the water space in said boiler and having an outlet 50 through the top of said combustion chamber which is in communication with the steam space in said boiler.

13. A locomotive boiler having a boiler shell, a combustion chamber extended forwardly within said shell from the rear end thereof and spaced therefrom and providing a water space under and a steam space above 55 said combustion chamber, a grate at one end of said chamber for supporting the fire, a rear tube sheet which forms the front wall of 60 said chamber, evaporating tubes terminated at said tube sheet, and a superheater located in said combustion chamber between said grate and said tube sheet for superheating 65 the steam supplied by said boiler, said super-

heater having saturated and superheated steam headers which are located in said combustion chamber respectively near said tube sheet and said grate, and said superheated steam header having a water jacket that is interposed between the fire and said header and has an inlet at the bottom that is in communication with the water space under said combustion chamber and an outlet at the top that is in communication with the steam space 70 above said combustion chamber.

14. A locomotive boiler having a combustion chamber, a superheater therein having saturated and superheated steam headers and superheater tubes connected between them, 80 said superheated steam header being extended transversely of said combustion chamber and supported both by the bottom and the top wall thereof and having a water jacket which surrounds at least a part of the steam space thereof and is in communication at the bottom and top thereof through the wall of the combustion chamber respectively with the water and the steam space under and on top of said combustion chamber.

In testimony whereof, I have signed my name to this specification.

EUGENE L. SCHELLENS.
